UNITED STATES PATENT OFFICE.

WILLIAM A. KREIDLER, OF LAKE BLUFF, ILLINOIS, ASSIGNOR, BY MESNE ASSIGNMENTS, TO LACKAWANNA STEEL COMPANY, OF NEW YORK, N. Y., A CORPORATION OF NEW YORK.

SHEET-PILING.

1,206,862.

Specification of Letters Patent.

Patented Dec. 5, 1916.

Original application filed July 17, 1905, Serial No. 269,927. Divided and this application filed June 4, 1906, Serial No. 320,045. Renewed February 23, 1916. Serial No. 80,093.

To all whom it may concern:

Be it known that I, WILLIAM A. KREIDLER, citizen of the United States, residing at Lake Bluff, in the county of Lake and State 5 of Illinois, have invented a certain new and useful Improvement in Sheet-Piling, of which the following is a full, clear, concise, and exact description, reference being had to the accompanying drawings, forming a 10 part of this specification.

My invention relates to sheet piling, its object being to provide improved construction and arrangement of the sections composing it.

15 In the accompanying drawing my invention is illustrated and the figure thereof shows the top view of my improved piling.

Each alternate section of the arrangement shown is an ordinary channel beam 1, the 20 other sections being of special construction which forms the feature of my invention. Each of the beams 2 consists of a web or plate 3 having at each end a lateral projection 4 terminating in a hook 5. These 25 flanges may be on the same side of the web 3 and the hooks are turned outwardly. The flanges or lateral extensions 4 are set inwardly a distance from the ends of the web part, thus leaving a shelf or extension 6 30 below each hook and the flanges 7 of the sections 1 engage in the pockets formed by the hooks, flanges and extensions and the sections are thus rigidly locked together. The web or body part of the sections 1 are 35 offset preferably the thickness of the extensions 6, as shown, whereby the wall upon assembly of the sections will present a plane unbroken face. Other changes may also readily be made without departing from the 40 spirit of my invention and.

I claim as new and desire to secure by Letters Patent:

1. In a sheet piling wall, a section 45 consisting of a web provided at each end with a lateral extension terminating in a hook and a longitudinal extension below each

hook forming a continuation of the web of the section, and an adjacent section having a web provided at each end with a straight lateral projection for engaging within the 50 hook and longitudinal projection of the first section, a section of the web of the second section opposite the straight lateral projection being offset the thickness of the longitudinal projection of the first section to form 55 a recess for receiving said longitudinal projection whereby the wall presents a plane unbroken face.

2. A sheet piling wall composed of main sections having lateral extensions with 60 hooked ends extending from the web adjacent to but a short distance within the lateral edges of the web, and angle beams adapted to engage with the hooks and having the ends of their webs offset about to 65 correspond to the thickness of the main section web.

3. A sheet piling wall composed of main sections and of intermediate sections, both of 70 said sections consisting of substantially straight webs with interlocking elements at both edges of the web, the interlocking elements of the main section consisting of lateral extensions having hooked ends and of longitudinal extensions below each hook, 75 and the interlocking elements of the intermediate sections consisting of straight lateral extensions adapted to engage in the recesses formed by the hooked extensions and the longitudinal extensions of the main sections, the ends of one of said sections being offset so that the webs of both the main and 80 the intermediate sections shall be in the same plane when the sections are assembled in the 85 wall.

In witness whereof, I hereunto subscribe my name this 2nd day of June A. D., 1906.

WILLIAM A. KREIDLER.
